DESIGN FOR A TOY BALLOON

Ralph T. Scantlebury, Ashland, Ohio, assignor to
The Toycraft Rubber Company, Ashland, Ohio,
a corporation of Ohio

Application July 30, 1936, Serial No. 64,137

Term of patent 3½ years

To all whom it may concern:

Be it known that I, Ralph T. Scantlebury, a citizen of the United States, residing at Ashland, in the county of Ashland and State of Ohio, have invented a new, original, and ornamental Design for a Toy Balloon, of which the following is a specification, reference being had to the accompanying drawing, forming part thereof.

Fig. 1 is a side elevation of the balloon when inflated;

Fig. 2 is a side elevation of the balloon when deflated.

I claim:

The ornamental design for a toy balloon, as shown.

R. T. SCANTLEBURY.
